[57] **CLAIM**

The ornamental design for a combined spotlight and recharger base therefor, as shown and described.

DESCRIPTION

FIG. 1 is a front perspective view of the combined spotlight and recharger base therefor according to my new design;

FIG. 2 is a rear perspective view of the spotlight and base shown in FIG. 1;

FIG. 3 is an enlarged plan view of the base shown in FIG. 1;

FIG. 4 is a front elevational view thereof; and,

FIG. 5 is a side elevational view thereof.

The broken lines are shown for illustrative purposes only and form no part of the claimed design.

FIG. 2

FIG. 1

FIG. 3

FIG. 4

FIG. 5
